UNITED STATES PATENT OFFICE.

ALBERT E. McMANUS, OF DULUTH, MINNESOTA.

LAMINATED SPRING.

1,221,071.

Specification of Letters Patent.

Patented Apr. 3, 1917.

Application filed October 5, 1916. Serial No. 123,867.

To all whom it may concern:

Be it known that I, ALBERT E. McMANUS, a citizen of the United States, residing at Duluth, in the county of St. Louis and State 5 of Minnesota, have invented new and useful Improvements in Laminated Springs; and I do hereby declare the following to be a full, clear, and exact description of the invention, such as will enable others skilled 10 in the art to which it appertains to make and use the same.

My invention relates to laminated or plural leaf springs and has for its object the provision of a plural leaf spring which may 15 be easily and conveniently oiled and in which the oil receiving passages may be readily cleaned without taking the spring apart. It consists of the constructions, combinations and arrangements of parts here- 20 inafter described and claimed.

In the drawings, Figure 1 is a side elevation of one form of elliptical spring in which my invention may be embodied. Fig. 2 is a central vertical cross section of said 25 spring showing one form of my invention embodied therein. Fig. 3, is a central vertical cross section of the lower bow of an elliptical spring, showing a modified form of my invention embodied therein.

30 In the drawings each of the leaves 1 and 2 composing the upper and lower bows respectively of said spring (Fig. 2) has formed upon its upper face at one or both sides, a longitudinally directed shallow bead 35 or rib 1^a, 2^a, except the top leaf of each bow, from which such bead may, if desired, be omitted. In the preferred form of my invention (Fig. 2) each successive leaf in the bottom bow is slightly narrower than the 40 leaf next below it, whereby oil receiving channels 2^b are formed between the beads on each beaded leaf and the sides of the next superposed leaf. In said preferred form, each successive leaf in the upper bow is also 45 slightly narrower than the leaf next below it in the same bow, whereby oil receiving channels 1^c, are formed between the beads on each beaded leaf and the sides of the next super- 50 posed leaf. The floors of said channels are preferably flush with the contacting faces of the respective leaves. In the modified form of my invention (Fig. 3) the leaves are of substantially uniform width, and are provided with beads substantially similar to

those provided in the preferred form of 55 spring; but in said modified form the lower edges of each leaf in the lower bow, except the bottom leaf, are undercut or beveled inwardly and downwardly as at 2^c so as to provide oil receiving spaces or channels between 60 the beads of each beaded leaf and the overhanging sides of the next superposed leaf.

In operation, oil is injected into the several channels or oil receiving spaces, and thence runs between the opposing faces of 65 the respective leaves, the spread of the oil being facilitated by the action of the leaves upon each other when the spring is being expanded or contracted. If said oil receiving channels or spaces become choked with 70 dust, they may easily be scraped clean with a screw driver or sharp piece of wood or other convenient implement.

While I have shown certain forms of plural leaf springs embodying my invention I 75 do not desire to limit myself to such forms only. It is obvious that my invention may be modified in details or embodied in other forms of plural leaf springs, within the scope and spirit of certain of my claims. 80

What I claim is,

1. A spring comprising a plurality of superposed leaves, some of said leaves having a longitudinally directed bead formed upon their upper surfaces at one side, the 85 upper edge of each such bead being spaced from the side of the respectively next superposed leaf.

2. A spring comprising a plurality of superposed leaves, some of said leaves being 90 undercut at one side said undercut portion being spaced from the respectively next underlying one of said leaves.

3. A spring comprising a plurality of superposed leaves, each two adjoining ones 95 of said leaves being adapted in coöperation with each other to form an open groove or channel at one side of said spring, the bottom of such channel being flush with upper face of the central portion of the lower one 100 of the two leaves by which such channel is formed.

In testimony whereof, I hereunto affix my signature, in presence of two witnesses.

ALBERT E. McMANUS.
